UNITED STATES PATENT OFFICE.

ADAM A. SERVA, OF CANTON, OHIO, ASSIGNOR TO THE UNITED ELECTRIC COMPANY, OF CANTON, OHIO, A CORPORATION OF OHIO.

DUST COLLECTOR.

Application filed January 26, 1924. Serial No. 688,717.

This invention relates to improvements in dust collectors for vacuum cleaners.

The objects of the improvement are to provide a dust collector including an exhaust manifold into which the dust laden air is exhausted from the fan, said manifold extending into the middle portion of an upright bag, which may be pervious, to permit the heavy dirt and dust which enters the manifold to settle in the lower portion of the bag while the air may escape through the walls of the bag.

The above and other objects may be attained by providing a vertical bag into the middle portion of which is extended a T-elbow leading from the outlet of the fan chamber, the opposite ends of the T-elbow, the stem of which is flared from the fan casting, being directed toward the ends of the bag.

A practical embodiment of the invention is illustrated in the accompanying drawings, in which—

Figure 1 is a side elevation of a vacuum cleaner of the truck type, provided with the improved dust collector, one wheel of the truck being removed for the purpose of illustration;

Fig. 2, a section on the line 2—2, Fig. 1;

Fig. 3, a view similar to Fig. 2, showing a modified form of connection between the fan chamber and bag;

Fig. 4, a detached, perspective view of the clamp for the lower end of the bag;

Fig. 5, a side elevation of the bag, parts being broken away to illustrate the T-elbow which is shown in section;

Fig. 6, a view similar to Fig. 5, showing the bag clamped around the upper end of the T-elbow;

Fig. 7, a side elevation of a modified form of bag having straight sides; and

Fig. 8, a detail front elevation of the corset for protecting the middle portion of the bag.

Similar numerals indicate corresponding parts throughout the drawings.

The invention is illustrated as applied to the truck type of portable vacuum cleaner which includes the tank 1, supported upon the wheels 2, and provided with the air inlet 3, to which may be attached a hose hav-

ing a nozzle or cleaning tool of any accepted type for engagement with the floor or other surface to be cleaned.

This tank communicates in usual manner with the fan chamber 4, in which is mounted a rotary suction fan of usual construction, driven by the motor 5. This much of the construction may be varied, and in its details forms no part of the present invention.

To the outlet neck 6, or 6^a of the fan chamber is attached an elbow 7 or 7^a, to the rear end of which is connected, as by the bayonet swivel shown, the reduced extremity 55 of the stem of the T-elbow 8, the enlarged T-head 9 thereof being preferably located in the longitudinal center of the device as shown in Figs. 2 and 3.

This T-elbow is extended into the middle 70 portion of an upright dust collector bag 10 or 10^a, preferably at a point slightly below the center of the bag, as shown in the drawings. A neck 11 or 11^a may be formed in the middle portion of the bag to receive the T- 75 elbow, a clamping ring 12 or the like, being provided around said neck for securing the same upon the elbow.

The truck may be arranged to be manually propelled over the floor by means of a U-shaped handle 13, connected at its forward ends to the tank or other portion of the truck and straddling the dust collector bag, with a bracket 14 mounted upon said handle engaging the loop 15 at the upper end of the 80 bag for supporting the same in upright position.

The lower end of the bag, which is preferably provided with an opening to permit dust and dirt to be removed therefrom, is 85 normally closed by suitable detachable clamping means, such as the bifurcated spring clamp 16 which is provided with the clamping bolt 17 and wing nut 18.

A swivelled front castor 19 may be provided for supporting the forward portion of the truck and assisting in steering the same as it is propelled across the floor.

The dust collector bag may be reduced at its central portion as shown in Figs. 5 100 and 6, and if desired, a ring 20 may be provided to bind this reduced portion of the bag to the vertical portion of the T-elbow. The bag may also be straight from top to

bottom as shown in Fig. 7, the T-elbow being spaced from the side walls thereof, permitting dirt and dust to pass downward from the upper portion of the bag around the outside of the T-elbow without interference from the air blast discharged through said elbow.

For the purpose of supporting the reduced middle portion of the bag as shown in Fig. 5, a corset 21 may be provided around the same. This corset may be formed of pervious material, such as wire mesh or perforate sheet metal, split vertically upon its front side as shown at 22, and provided with the split nipple 23 surrounding the stem of the T-elbow.

As shown in Fig. 5, a concavo convex shield 25 may be provided in the upper end of the bag to prevent the same from lapsing, this shield being connected in any suitable manner to the loop 15 by which the bag is supported.

This dome shield extends a substantial distance down around and within the sides of the bag to distend the same, is preferably pervious, being formed of wire mesh, perforate sheet metal or the like, in order to permit the air to pass freely through this portion of the wall of the bag.

The dust laden air which is expelled from the fan chamber expands as it passes through the flared T-elbow, to reduce the pressure gradually as the air passes from the exhaust of the fan chamber through the enlarged vertical portion of the T-elbow.

The air entering the vertical portion 9 of the T-elbow will exhaust upward and downward, the heavier dirt dropping into the lower portion of the dust collector bag, while only the lighter particles of the dust will pass upward into the upper portion of the bag, the air escaping through the walls thereof; and the lighter dirt which is carried into the upper portion of the bag will later

drop around the outside of the T-elbow into the lower portion of the bag.

The T-elbow serves not only as a support by which the middle portion of the bag can be attached to the exhaust pipe of the cleaning machine, but it also serves as a shield to prevent the dust and dirt laden air from impinging and cutting out the side wall of the bag, until after it has been deflected either upward or downward into the end portion of the bag.

The upper portion of the bag may be shaken or tapped at any time, causing all of the fine dust which may adhere to the walls of the upper portion of the bag, to fall into the bottom of the bag, which may be easily opened and emptied whenever necessary by merely removing the clamp 16.

I claim:—

1. In a vacuum cleaner or the like, an exhaust manifold arranged to discharge in opposite directions, and a dust bag surrounding the manifold and spaced therefrom with its end portions extending in the directions of discharge.

2. In a vacuum cleaner or the like, an exhaust manifold arranged to discharge in different directions, a dust bag surrounding the manifold with its end portions extending in the directions of discharge, and a corset surrounding the middle portion of the dust bag.

3. In a vacuum cleaner or the like, an exhaust manifold arranged to discharge in different directions, a dust bag surrounding the manifold with its end portions extending in the directions of discharge, said dust bag being reduced at its middle portion, and a corset surrounding the reduced portion of the dust bag.

In testimony that I claim the above, I have hereunto subscribed my name.

ADAM A. SERVA.
